2 Sheets-Sheet 2

UNITED STATES PATENT OFFICE.

HENRY P. FIELD, OF BERWICK, PENNSYLVANIA, ASSIGNOR TO AMERICAN CAR AND FOUNDRY COMPANY, OF NEW YORK, N. Y., A CORPORATION OF NEW JERSEY.

MINE CAR.

Application filed July 20, 1926. Serial No. 123,738.

In the drawings:

Fig. 1 is a view partly in side elevation with a wheel and part of an axle broken away and partly in longitudinal section of a 5 drop bottom mine car constructed in accordance with this invention;

Fig. 2 is a partial longitudinal section taken at one of the axles on the line 2—2 of Fig. 3, the drop doors being shown in 10 closed position;

Fig. 3 is a partial transverse section taken on the line 3—3 of Fig. 2;

Fig. 4 is a partial horizontal section taken on the line 4—4 of Fig. 2;

15 Fig. 5 is a partial longitudinal section taken on the line 5—5 of Fig. 3;

Fig. 6 is a view similar to Fig. 2 showing in solid lines one door in a dropped position and the latch operated by that door in position to release the adjacent door and showing in dotted lines the adjacent door in closed position;

Fig. 7 is a view similar to Fig. 2 of a modified construction;

25 Fig. 8 is a fragmentary section taken longitudinally of the car at one of the door latches, as on the line 8—8 of Fig. 9, and shows a latch in engagement with a lug or projection on a door, and

30 Fig. 9 is a fragmentary section taken transversely of the car at one of the door latches, as on the line 9—9 of Fig. 8.

This invention relates to mine cars of the drop-bottom type wherein the bottom comprises a plurality of doors pivotally mounted at one end and controlling the latch of an adjacent door, and it is an object of this invention to provide improved means for hanging the doors and for operating the 35 latch of the adjacent door. It is also an object of this invention to provide an improved latching means and a protecting support therefor.

40 This invention is shown applied to a mine car of the type shown in my co-pending application, Serial No. 81,255, filed January 14, 1926, of which application this application is in part a division. The mine car shown comprises side sills 1 and end sills 2 45 both being of channel shape and having their flanges projecting outwardly. The side sills and end sills are secured together at

their ends by angle members 4 and the end sills support bumpers 5 and drawbars 6 of suitable construction, the bumpers and drawbars being provided with openings for the usual coupling pins 8. To the upper flanges 10 of the side sills 1 are secured the inner edges of the side sheets 12, the side sheets 12 being joined at their ends by the end sheets 14 secured thereto by the inwardly bent flanges 15 of the end sheets. The end sheets 14 are spaced inwardly from the end sills 2 and extend downwardly between the side sills 1. The car is supported on wheels 16 mounted on axles 18 which extend through openings in the side sills 1 and are journaled in boxes 19 secured to the side sills.

45 The floor of the car consists of a plurality of doors 20, 22 and 24 formed of sheet metal and having their side edges bent upwardly to form stiffening flanges 26 which extend substantially from end to end of the doors and project above the lower edges of the side sills to prevent loss of the contents of the car between the side sills and the doors. The door 20 is provided with hinge straps 28 which engage a shaft 30 mounted in bearing brackets 32 secured to the lower flanges 34 50 of the side sills. In the construction shown in Figs. 1 to 6 the doors 22 and 24 are provided with hinge straps 35 which engage short shafts 36 having their outer ends journaled in bearing brackets 38 secured to the flanges 34 of the side sills and their inner ends journaled in bearing brackets 40. The bearing brackets 40 are provided with outwardly projecting flanges 42 by which they are secured to outwardly projecting flanges 44 of channel-shape braces or hood members 46 which extend between the side sills and are provided at their ends with laterally extending flanges 48 by which the members 46 are secured to the webs 50 and upper flanges 55 55 of the side sills 1. The central portions of the shafts 36 are made angular to fit correspondingly shaped openings in the hinge members 35 and are provided at their inner ends with cotter pins 51 to prevent the withdrawal of the shafts 36 from the hinge members.

60 At one side each hinge member 35 is provided with a gear segment 52 formed inte-

gral therewith and meshing with a correspondingly formed gear segment 54 formed integral with a latch member 56. The latch members 56 are journaled on pins 58 mounted in the side sills 1 and the hood members 46, the hood members 46 being enlarged at their ends to provide openings to receive the latch members 56. The latch members comprise curved latch portions 60 which project inwardly from the gear segments 54 to engage beneath lugs or projections 62 carried by straps 64 secured to the doors 20 and 22 adjacent their free edges, the corners of the doors being cut away to provide openings 15 to receive the lugs 62 and latching members 56. Movement of the latch members 56 along the pins 58 is prevented by means of sleeves 66 and withdrawal of the pins is prevented by means of the cotters 68 and heads 20 69. The free edge of the door 24 is provided with an outwardly projecting lug 70 engaged by a latch 72 which may be of any desired construction, such as is shown in the patent to Nichols No. 1,534,135 of April 21, 25 1925.

In the modified construction shown in Fig. 7, the door 22' is provided with a hinge member 35' which is journaled upon the car axle 18', the hinge member 35' being provided with a gear segment 52' which engages the gear segment 54' of a latch member 56' of construction identical with the construction shown in Figs. 1 to 6. In this modification, however, in order to position 30 the door at the proper height above the rails, the strap 64' carrying the lug 62' is placed on top of the door sheet instead of underneath as in the other construction. Otherwise, this modification is identical with the 35 structure shown in other figures.

In the operation of the device, assuming the doors to be closed as shown in Fig. 1, operating the latch 72 will release the door 24 permitting the door to drop and operate 40 the gear segments 52 on the hinge members of the door 24. Operating these gear segments 52 will operate the gear segments 54 and positively retract the latch portions 60 of the latch members 56 from beneath the 45 lugs 62 on the door 22 whereupon the door 22 will drop and in like manner operate the latch members 56 to release the door 20. The doors will be returned to closed position by a suitable device such as is shown in 50 the patent to Nichols, mentioned above, and they will be returned in the reverse order, the door 20 being raised to the fully closed position and then the door 22 being raised. Raising the door 22 will cause the operation 55 of the latch members 56 to engage with the lugs 62 carried by the door 20 and the raising of the door 24 will cause the operation of the latch members 56 to engage with the lugs 62 carried by the door 22. Raising the 60 door 24 to the fully closed position also

causes the lug 70 carried by the door 24 to be engaged by the latch member 72 which retains the door 24 in the fully closed position thereby retaining the doors 22 and 20 in the fully closed position. 70

What is claimed is:

1. In a car, a pivotally mounted door, a pivotally mounted latch for said door, a second pivotally mounted door and cooperating gearing on said latch and said second door. 75

2. In a car, a pivotally mounted door, a pivotally mounted latch for said door, a second pivotally mounted door, cooperating gearing on said second door and latch and a hood shielding said latch and gearing. 80

3. In a car, a pivotally mounted door having a projection thereon, a pivotally mounted latch engageable with said projection, a second pivotally mounted door and cooperating gearing on said latch and said second door. 85

4. In a car, a pivotally mounted door having a projection adjacent its free edge, a pivotally mounted latch having a flange engageable with said projection, a second pivotally mounted door, a hinge strap for said second door and co-operating gearing on said latch and hinge strap. 90

5. In a car having spaced sills, a wheel carrying axle mounted in said sills, a flanged hood for said axle, bearing brackets carried by said hood and a door pivotally supported by said brackets. 95

6. In a car having spaced sills, a wheel carrying axle mounted in said sills, a flanged brace connecting said sills and extending to opposite sides of said axle, bearing brackets carried by said brace beneath said axle and a door pivotally supported by said brackets. 100

7. In a car having spaced sills, wheel carrying axles mounted in said sills, flanged hoods for said axles, bearing brackets carried by said hoods, doors pivotally supported by said brackets and latches for some of said doors pivotally mounted between said hoods and said sills and operatively connected to others of said doors. 110

8. In a car having spaced sills, wheel carrying axles mounted in said sills, flanged braces connecting said sills and extending to opposite sides of said axles, bearing brackets carried by said braces beneath said axle, doors pivotally supported by said brackets and latches for some of said doors pivotally mounted between said braces and sills and operatively connected to others of said doors. 115

9. In a car having spaced sills, a wheel carrying axle mounted in said sills, a flanged hood for said axle connecting said sills, and door supporting bearing brackets carried by said hood, said hood being enlarged at its ends to provide openings for door latches. 120

10. In a car having spaced sills, a wheel carrying axle mounted in said sills, a flanged hood for said axle connecting said sills, 125

bearing brackets connecting said hood flanges and a door pivotally supported by said bearing brackets.

11. In a car having spaced sills, a brace connecting said sills, bearing brackets carried by said brace and a door pivotally supported by said bearing brackets.

12. In a car having spaced sills, a flanged brace connecting said sills, bearing brackets connecting said brace flanges and a door pivotally supported by said bearing brackets.

13. In a car having spaced sills, a flanged brace connecting said sills, bearing brackets connecting said brace flanges and a door piv-

otally supported by said bearing brackets, 15 said brace being enlarged at its ends to provide openings for door latches.

14. In a car, a pivotally mounted door having its face edge cut away forming openings at the corners, lugs carried by said door 20 and projecting into the openings, latches engaging said lugs, a hood covering said latches and openings and a second door pivotally supported from said hood and operatively connected to said latches. 25

In witness whereof I have hereunto set my hand.

HENRY P. FIELD.
